UNITED STATES PATENT OFFICE.

WINFIELD J. FISH, OF HAMILTON, OHIO, ASSIGNOR OF ONE-HALF TO ABNER CRESS,
OF HAMILTON, OHIO.

PACKING BOX FOR PULP AND PAPER BEATERS.

Application filed February 6, 1925. Serial No. 7,329.

To all whom it may concern:

Be it known that WINFIELD J. FISH, a citizen of the United States, residing at Hamilton, in the county of Butler and State of Ohio, has invented certain new and useful Improvements in Packing Boxes for Pulp and Paper Beaters, of which the following is a specification.

This invention relates to new and useful improvements in packing boxes especially adapted for pulp and paper beaters, and has for one of its principal objects to serve as support and means of adjustment for the shaft of the beater.

Another object is to provide a device to relieve shocks and strains on the beater shaft.

A still further object of the invention is to provide a packing box of the above mentioned character, which is simple in construction, inexpensive, strong, durable and further well adapted for the purposes for which it is designed.

With these and other objects in view, my invention consists in the novel features of construction, combination and arrangement of parts as will be hereinafter referred to and more particularly pointed out in the specification and claims.

In the accompanying drawings, forming a part of this application,—

Figure 1 is a side view of the invention applied to a beater;

Figure 2 is an enlarged side elevation of the device;

Figure 3 is a vertical section on the line 3—3 of Fig. 2;

Figure 4 is a horizontal section taken on the line 4—4 of Fig. 2;

Figure 5 is a detail view of the split base plate holding the packing ring;

Figure 6 are details of the split inner and outer housing rings;

Figure 7 is a detail of the gland ring separated; and

Figure 8 is a detail section showing the adjustable attaching means for one end of the vertical coil springs.

Referring to the drawings, in which similar reference characters designate similar parts throughout the several views, 1 represents the beater which has a conventional hood 2 covering the main portion of the beater. The packing box 3 is fastened to the side of the beater by means of two verti-

cal plates 4 which are bolted to the side of the beater, as shown at 5. The beater shaft 6 is disposed centrally through the packing box which is adapted to move up and down and sideways according to the motion of the shaft. When the beater is filled, the shaft motion varies and my packing box is adapted for adjustment of such motion. The packing box has two rectangular base plates 7 and 8 which move vertically in the inner grooves 9 of the plates 4. There is sufficient space between the sides of these plates and the grooves for lateral movement, due to the movement of the beater shaft. These plates are split centrally and vertically at 10 and have circular openings 11 and 12 for the disposition of the beater shaft.

The outer plate 8 has the larger circular opening 12 to form an annular groove 12' to hold a packing ring 14 which is seated on one side against plate 8 and on the other side by an inner housing ring 15. This ring is centrally split, as shown at 16. An outer housing ring 17 is provided which fits snugly against the outer circumference of the housing ring 15. This outer ring 17 is also centrally split as shown at 18.

A centrally split gland ring 19 fits over the housing rings 15 and 17 and has six flanges as shown at 20. These flanges have apertures 21 through which extend bolts 22. The inner ends of these bolts 22 are countersunk in the base plate 7 and fasten the two base plates. The outer end of the bolts 22 have nuts 23 which hold in position coil springs 24. There are a series of bolts 25 fastening the gland ring to the inner housing ring 15.

On the top and bottom of the plates 4 are fastening hooks 26 to hold the ends of the spiral springs 27 which are fastened to the base plate by hooks 28.

On the inner sides of the plates 4 are fastened angle plates 29 holding adjustable screw hooks 30 to which are fastened vertical coil springs 31 which fasten to bolts 22.

The set of coiled springs on the upper and lower sides of the base plate together with the two vertical coiled springs make provision for the vertical and horizontal adjustment of the packing box.

From the foregoing description of the construction of my improved device, it will

be seen that I have provided a simple, inexpensive and efficient means for carrying out the objects of the invention.

While I have particularly described the elements best adapted to perform the functions set forth, it is obvious that various changes in form, proportion, and in the minor details of construction may be resorted to, without departing from the spirit 10 or sacrificing any of the principles of the invention.

Having thus described my invention, what I claim is:—

1. In a packing box apparatus for beater shafts, a pair of parallel guide plates permanently secured in position, a packing element slidably mounted between said guide plates comprising a plurality of superimposed plates and rings, and spring means 15 between said guide plates and packing element to yieldingly retain the latter in position, as and for the purposes described.

2. In a packing box apparatus for beater shafts, a pair of parallel guide plates, a packing element slidably mounted between said guide plates, said packing element comprising a plurality of superimposed plates and rings, and a plurality of adjustable coil springs connecting the packing element 25 with said guide plates yieldingly retaining said packing element in position, as and for the purposes described.

3. In a packing box apparatus for beater shafts, a pair of parallel guide plates permanently secured in position, a packing element comprising a pair of base plates having enlarged and registering central openings therein for the reception of the beater shaft therethrough, housing rings applied 35 to said base plate, a gland ring superposed upon said housing rings, the base plates of said packing element being slidably mounted between said guide plates, and spring means between said packing element and said guide plates to yieldingly retain the former in position within the latter.

4. In a packing box apparatus for beater shafts, a pair of parallel guide plates permanently secured in position, a packing element comprising a pair of base plates having enlarged and registering central openings therein for the reception of the beater shaft therethrough, housing rings applied 45 to

to said base plate, a gland ring superposed upon said housing rings, the base plates of 55 said packing element being slidably mounted between said guide plates, coil springs between the ends of said base plates and said guide plates, and additional coil springs between said guide plates and said 60 gland ring, as and for the purposes described.

5. In a packing box apparatus for beater shafts, a pair of parallel guide plates permanently secured in position, a packing element comprising a pair of superposed and split base plates provided with registering central openings adapted to receive the beater shaft therethrough, the opening of one of said plates being of greater diameter 70 than the other, a packing ring disposed within the periphery of the base plate having the larger opening therein, a pair of inner and outer housing rings applied to the last mentioned base plate and packing 75 ring, a gland ring superposed upon said housing rings, and means for securing said base plates and rings together, said base plates being slidably disposed between said guide plates, and spring means between said 80 guide plates and said packing element to yieldingly retain the latter in position, as and for the purposes described.

6. In a packing box apparatus for beater shafts, a pair of parallel guide plates permanently secured in position, a packing element comprising a pair of superposed and split base plates provided with registering central openings adapted to receive the beater shaft therethrough, the opening of 85 one of said plates being of greater diameter than the other, a packing ring disposed within the periphery of the base plate having the larger opening therein, a pair of inner and outer housing rings applied to the last mentioned base plate and packing ring, a gland ring superposed upon said housing rings, pairs of coil springs between the ends of said guide plates and base plates, and additional coil springs between said 95 guide plates and said gland ring, as and for the purposes described.

In testimony whereof I affix my signature.

WINFIELD J. FISH.
